UNITED STATES PATENT OFFICE

2,541,054

ADJUSTABLE ECCENTRIC CHUCK

Stephen C. Haynosch, Cleveland, Ohio

Application October 14, 1947, Serial No. 779,766

2 Claims. (Cl. 279—6)

1

This invention relates to chucks and particularly to eccentric chucks.

The primary object of this invention is to provide an adjustable eccentric chuck for boring cutters that can be adapted to bore holes of various diameters with the same cutter.

Another object is to provide an adjustable eccentric chuck constructed to support a boring cutter in adjusted positions with substantially the same rigidity as if it were supported by a one-piece chuck.

A further object is to provide a device of the type stated that is simple and economical of construction; and also easy to maintain in accurate working condition.

These and other objects of the invention will become apparent from a reading of the following specification and claims, together with the accompanying drawings in which like parts are referred to and indicated by like reference characters and wherein:

Figure 1 is a front elevation of the adjustable eccentric chuck constituting this invention, with parts broken away;

Figure 2 is a rear elevation of the same with portions broken away;

Figure 3 is a left end view of the chuck in its extreme eccentric condition;

Figure 4 is an exploded view of the device;

Figure 5 is a vertical sectional view taken substantially along the line and in the direction of the arrows 5—5 of the Figure 1;

Figure 6 is a vertical sectional view taken substantially along the line and in the direction of the arrows 6—6 of the Figure 3;

Figure 7 is a cross sectional view taken along the line and in the direction of the arrows 7—7 of the Figure 1;

Figure 8 is a cross sectional view taken along the line and in the direction of the arrows 8—8 of the Figure 1; and

Figure 9 is a cross sectional view taken along the line and in the direction of the arrows 9—9 of the Figure 1.

Adjustable eccentric chucks are old in the art, but difficulty has been found in constructing these devices so that they will combine precision in working to close dimensions with simplicity of structure and consequent low cost.

The present invention is designed to be made from cylindrical bar stock and except for the guideways requires only simple turning, facing and threading operations in its construction.

The chuck as illustrated in the Figure 1 of the drawings is composed of three major parts or

2

members, a body, a tool holder and a collar, broadly indicated by the reference characters 10, 20 and 30 respectively.

The body member 10 is provided with a cylindrical shank portion 11 adapted to accurately fit the opening of a standard size tail stock or socket 17 of a machine tool. When so positioned in a machine tool, the shank 11 serves as the axis of rotation of the device. The body is also provided with an annular shoulder flange 15 and a threaded cylindrical neck 16 which are concentric with the longitudinal axis of the body member as is shown most clearly in the Figure 4. A tongue 12 extends transversely of the longitudinal axis of the body member. The tongue shown is T-shaped in cross section, although any other suitable shape such as a dove tail may be used if desired. Reference character 14 indicates a threaded hole which extends longitudinally of the tongue 12 as shown in the Figures 3, 4, 5, 6 and 9.

The tool holder 20 is also cylindrical in shape and has a tool holding means or socket 21, including a set screw 22, of conventional type for holding a boring cutter 40 as shown.

A groove 23 of a T-shaped configuration matching that of the tongue 12 extends transversely of the longitudinal axis of the tool holder 20 and slidably engages the tongue 12 in an accurate fit. A screw 26 is seated in the bearing block 27 in threaded engagement with the hole 14 of the tongue 12 as shown in the Figures 1, 2, 3, 4, 5, 6 and 9. The tool holder has a plane bearing surface 25.

An annular threaded collar 30 and a bearing washer 32 are mounted on the threaded neck 16 between the bearing surface 25 and the body flange 15.

When the body 10 and tool-holder 20 are concentrically aligned as designated by the reference character 20a in the Figures 3 and 5, the boring cutter 40a will cut a hole of minimum diameter. The tool holder may be moved into the eccentric position designated by the reference character 20 by inserting a socket wrench into the socket 28 at the outer end of the screw 26 and rotating the screw. This causes the tool holder to slide longitudinally of the tongue 12. This motion carries the boring cutter to a position designated by reference characters 40, which is eccentric of the axis of the body shank 11. The boring cutter will then describe a circle of larger diameter and therefore cut a larger hole. The radial movement of the tool holder 20 can be accurately determined by any one of a number of well known

means. A screw with forty threads to the inch and carrying a circular scale divided into twenty-five parts will give readings in $1/1000$ of an inch.

Once the tool holder has been located, the threaded collar 30 is screwed up tightly against the bearing washer 32 and bearing surface 25 of the tool holder 20. Socket holes 31 in the collar 30 provide anchor points for a spanner wrench. The abutting surfaces 13 and 24 of the tongue and groove 12 and 13 respectively are tightly locked together by the compressive action of the collar 30. The combined width of the collar 30 and bearing washer 32 is such that less than a quarter turn of the collar 30 is required to either lock or unlock the tool holder 20. This makes a rigid unit of the device regardless of the extent of the eccentricity of the setting of the boring cutter. Since the collar is circular, the locking pressure is exerted evenly and positively against the bearing surface 25. There is no danger of loosening or misalignment of the parts as in the case where a number of individual locking screws have to be drawn up evenly to assure that the setting of the boring cutter will be maintained.

The chuck can be used to hold cutters of any type that must be adjustably offset with respect to the rotational axis of the body member.

It will now be clear that there has been provided a device that accomplishes the objectives heretofore set forth. While the invention has been disclosed in its preferred form, it is to be understood that the specific embodiment thereof as described and illustrated herein is not to be considered in a limited sense as there may be other forms or modifications of the invention which should also be construed to come within the scope of the appended claims.

I claim:

1. An adjustable eccentric chuck, comprising in combination, a body member including a shank mountable in a machine and having a T-shaped tongue extending transversely of the axis of the

said body, and flange and threaded neck portions concentric with the said axis, a tool holder including means for holding a cutter and having a bearing surface, a groove portion slidably engaged with the said T-shaped tongue and a threaded means capable of moving the said tool holder longitudinally of the said tongue, and a threaded collar rotatably mounted on the threaded neck portion, intermediate the said flange and bearing surface, and engageable with the said bearing surface.

2. An adjustable eccentric chuck, comprising in combination, a body member including a shank mountable in a machine and having a dove tail shaped tongue extending transversely of the axis of the said body, and flange and threaded neck portions concentric with the said axis, a tool holder including means for holding a cutter and having a bearing surface, a groove portion slidably engaged with the said dove tail shaped tongue and a threaded means capable of moving the said tool holder longitudinally of the said tongue, and a threaded collar rotatably mounted on the threaded neck portion, intermediate the said flange and bearing surface, and engageable with the said bearing surface.

STEPHEN C. HAYNOSCH.
